No. 644,030.

F. S. HENNING.
SECTIONAL WATER HEATER.

Patented Feb. 20, 1900.

(Application filed Aug. 22, 1898. Renewed Jan. 13, 1900.)

(No Model.)

THE NORRIS PETERS CO., PHOTO-LITHO., WASHINGTON, D. C.

UNITED STATES PATENT OFFICE.

FREDERICK SAYERS HENNING, OF TORONTO, CANADA, ASSIGNOR, BY DIRECT AND MESNE ASSIGNMENTS, TO JAMES OLIVER BUCHANAN AND HARRY BOUGHTON-HODGINS, OF SAME PLACE.

SECTIONAL WATER-HEATER.

SPECIFICATION forming part of Letters Patent No. 644,030, dated February 20, 1900.

Application filed August 22, 1898. Renewed January 18, 1900. Serial No. 1,396. (No model.)

To all whom it may concern:

Be it known that I, FREDERICK SAYERS HENNING, marine engineer, of the city of Toronto, county of York, Province of Ontario, Canada, 5 have invented certain new and useful Improvements in Sectional Water-Heaters, of which the following is a specification.

My invention relates to sectional water-heaters, more particularly as heated by gaseous or liquid fuel; and the object is to devise a simple compact form of furnace having water-sections and combustion-chambers so constructed as to promote circulation and having the heat applied in a more direct and 15 economical method than at present in use; and it consists, substantially, in providing a plurality of similar interlocking water-sections provided with ingress-ports at lower levels, respectively, than the egress-ports and 20 water-chambers circling spirally upward from the one to the other, a double water-post, combustion-chambers between the sections, having suitable burners placed therein and being connected by inclined conical vents, suitable 25 ventilating-doors and fuel-regulating devices being provided, as hereinafter more particularly described, and shown in the drawings hereunto attached, in which—

Figure 1 is a sectional perspective view of 30 a furnace made in accordance with my invention, partially broken away to show more particularly its construction. Fig. 2 is a vertical cross-section of the double water-post. Fig. 3 is a front detail of the ventilating-doors. Fig. 4 is a vertical section of the gas-feed pipe and air-injector.

In the drawings like letters of reference indicate corresponding parts in each figure.

A is a sectional furnace having the similar 40 sections B. The water-chamber b of the section B is made in the form of a spiral, circling from the ingress-port b' at the rear upwardly around the whole of the section back to the egress-port b², situated at a higher level at the 45 rear, thus giving a continuous rise throughout each section from ingress to egress. The end walls b³ of the spiral water-chamber b are one over the other and are continued forwardly past the center, as the partition b⁴, to cause

the water all to flow well to the front in passing around the chamber. The central parts b⁵ of the floor and b⁶ of the roof of each section are preferably made horizontal, as shown, the latter acting as a support for the burner C and the former, which is made as thin as possible, receiving the flame from the burner below evenly throughout.

The peripheries of the sections B are provided with vertical flanges b⁷, the upper one having an external lip b⁸, into which fits the lower flange of the section above. These flanges hold the water-sections well apart and afford room for the burners C, located between, thus forming separate combustion-chambers between the several sections. A series of flues b⁹ are formed through each water-section, preferably larger at the bottom and contracted at the top, and all inclined in one direction, preferably toward the egress-port and parallel with the periphery, thus giving the gases passing through a rotary velocity similar to that of the water and also preventing the current from a lower vent passing directly through the similar one above.

The water-post D has two vertical channels 75 d and d', separated by the partition d³. The channel d is closed at the top, but opens into the collecting-cap d⁴, bolted to the bottom, into which the return-pipes E lead. The channel d' is closed at the bottom, but opens 80 into the distributing-cap d⁵, bolted to the top, from which the flow-pipes E' branch. These pipes lead throughout the house to be heated, are connected to radiators, and finally lead back to the furnace in the ordinary manner. 85

In the front of the channels d and d' are ports d⁶ and d⁷, so placed that when the water-post is bolted to the rear of the water-sections, the ports d⁶ and d⁷ come opposite the ingress and egress ports b' and b², respectively, of each section.

Suitable water-tight packing is used wherever the water-joints are made.

A suitable escape-cock d⁸ is located at the foot of the water-post D to drain off the water when desired.

In front of the combustion-chambers are doors F, provided with adjustable dampers f.

The frame f' on which the doors are hung serves to bind the sections together in front, the water-post serving the same purpose at the rear.

5 On the top of the top section I preferably place a suitable cover G, having the gas-vent g leading therefrom, and at the bottom a suitable base H is provided.

The burner C may be of any form and adapted to the use of gas or liquid, or even of solid fuel, or an electric heater might be used, the essential point of my invention being the application of heat directly and independently to each section.

15 Where gas is burned, I preferably use the ring-burners C, suitably supported so that the flame plays directly upon the thin flat parts b^5 of the bottoms of the sections B.

The supply-pipes c have shoulders c' , abutting bosses b^9 , formed on the peripheral flanges b^7 of the sections B, and projecting through are screwed into air-injecting cups C^2 , having ordinary circular dampers c^2 .

25 The external vertical gas-pipe C^3 has ordinary gas-cocks c^3 , supplied with suitable nozzles c^4 , which project through the dampers c^2 in the form of injectors, as shown in Fig. 4.

The gas may be regulated for each burner separately or may be regulated for all by the 30 main cock c^5 . I preferably also provide the supplemental cock c^6 , which is operated from any desirable part of the house by the rod c^7 , the farther end of which is supplied with an index-point c^8 and handle c^9 , and preferably 35 the adjustable rings c^{10} , which limit the rod's movement by contact with the intermediate supporting-ring c^{11} . The rings c^{10} may be so adjusted that on placing the index-point opposite certain indicating-marks the heat may 40 be regulated from "full on" or "low," or even turned out, if necessary.

For igniting the burners I attach to the gas-pipe the flexible gas-tube J, provided with a suitable cock j , and elongated nozzle j' , which 45 may be inserted through the door, as shown in Fig. 1.

By my invention a furnace is provided in which the heat is independently supplied to the water in each section, and the water as it 50 is heated rises in each section naturally to the egress-port on account of the upward inclination of the section. This facilitates the flow very greatly, particularly on starting and when very little heat is required, as during the spring and fall. Great economy of fuel is effected by the ready regulation of the combustion to the heating required. The heat may be applied to one or more sections, as required, the water from the heated sections 55 alone circulating through the pipes, that in the other sections lying more or less dormant. Cleanliness and ease of management are points in favor of my furnace, which may be placed in any convenient part of the house, such as the corner of a kitchen or hall.

What I claim as my invention is—

1. A water-heater comprising a plurality of hollow sections having each an ingress and an egress port adapted to allow water to flow through said sections and means for independently applying heat to the several sections for the purpose specified. 70

2. A water-heater comprising a plurality of hollow sections having each ingress and egress water-ports therefor, separate burners beneath the several sections, feed-pipes connecting the fuel-supply with said burners and means for causing mixed air and fuel to pass through said burners as and for the purpose specified. 75

3. A water-heater comprising a plurality of hollow sections having each ingress and egress water-ports therefor, burners beneath the several sections—pipes connecting burners with the fuel-supply—air-injectors and regulating-cocks interposed in the paths of said fuel, as and for the purpose specified. 80

4. A water-heater comprising a plurality of hollow water-sections with ingress and egress water-ports therefor the burners C—pipes c , 90 air-injectors C^2 cocks c^3 regulating-cock c^6 rod c^7 and regulator—as and for the purpose specified.

5. A water-heater comprising a plurality of hollow water-sections, ingress and egress water-ports therefor, combustion-chambers beneath the several chambers—doors and dampers therefor and separate burners supplied with fuel within the several combustion-chambers and flues leading from the several combustion-chambers, as and for the purpose specified. 95

6. In a water-heater the combination with a plurality of independent sections having hollow water-chambers—the ingress water-ports of which are respectively lower than the egress water-ports thereof—the water-chambers gradually rising from the one to the other of means for applying heat to the said water-chambers for the purpose specified. 105

7. A water-heater comprising a plurality of independent sections having spirally-shaped water-chambers with ingress water-ports respectively lower than egress-ports—the central parts of said water-chambers being horizontal—heaters placed beneath the several said central parts as and for the purpose specified. 115

8. A water-heater comprising a plurality of hollow water-sections—ingress and egress ports—and the double water-post D, the collecting and distributing caps d^4 and d^5 the draining-cock d^8 and means for applying heat to the water-sections, as and for the purpose specified. 120

9. A water-heater comprising a plurality of hollow water-sections—ingress and egress water-ports therefor combustion-chambers between said water-sections—doors and dampers to said combustion-chambers—flues connecting said combustion-chambers—the cap and gas-vent—and base-burners situated in 130

the several combustion-chambers, as and for the purpose specified.

10. In a water-heater the combination of a plurality of hollow water-sections—ingress and egress water-ports therefor the combustion-chambers—doors, dampers and vents therefor burners connecting with fuel-supply of the tube J cock j and nozzle j' , as and for the purpose specified.
11. In a water-heater in combination with a plurality of water-sections and intermediate air-chambers of inclined flues, connecting the air-chambers through the water-sections, and means for applying heat in the air-chambers

to the water-sections, as and for the purpose specified.

12. In a water-heater in combination with a plurality of water-sections and intermediate air-chambers of flues connecting the air-chambers, having the upper ends contracted and means for applying heat in the air-chambers, as and for the purpose specified.

Signed at Toronto, Canada, this 25th day of July, 1898.

FREDERICK SAYERS HENNING.

In presence of—

C. M. CANNIFF,
HENRY F. CODD.
